US00D873815S

(12) **United States Design Patent** (10) **Patent No.:** **US D873,815 S**
(45) **Date of Patent:** **** Jan. 28, 2020**

(54) **ELECTRONIC DEVICE**

(71) Applicant: **Amazon Technologies, Inc.**, Seattle, WA (US)

(72) Inventors: **Giles David Matthew McWilliam**, San Francisco, CA (US); **Christopher Green**, San Francisco, CA (US); **Gregory Michael Hart**, Mercer Island, WA (US); **Marc Rene Walliser**, San Francisco, CA (US); **Sun Joo Han**, San Francisco, CA (US)

(73) Assignee: **Amazon Technologies, Inc.**, Seattle, WA (US)

(**) Term: **15 Years**

(21) Appl. No.: **29/673,284**

(22) Filed: **Dec. 13, 2018**

Related U.S. Application Data

(62) Division of application No. 29/629,112, filed on Dec. 11, 2017, now Pat. No. Des. 841,644, which is a division of application No. 29/562,671, filed on Apr. 27, 2016, now Pat. No. Des. 806,066.

(57) **CLAIM**

The ornamental design for an electronic device, as shown and described.

DESCRIPTION

FIG. 1 is a bottom, front perspective view of an electronic device;

FIG. 2 is a top, back perspective view thereof;

FIG. 3 is a front view thereof;

FIG. 4 is a back view thereof;

FIG. 5 is a left-side view thereof;

FIG. 6 is a right-side view thereof;

FIG. 7 is a top view thereof; and,

FIG. 8 is a bottom view thereof.

The broken lines immediately adjacent the shaded areas represent the bounds of the claimed design while all other broken lines are directed to environment; the broken lines form no part of the claimed design.

1 Claim, 8 Drawing Sheets
